UNITED STATES PATENT OFFICE.

EDMUND RING, OF KINGSTON, WISCONSIN.

LOADING APPARATUS.

No. 817,274.

Specification of Letters Patent.

Patented April 10, 1906.

Application filed January 15, 1906. Serial No. 296,047.

To all whom it may concern:

Be it known that I, EDMUND RING, a citizen of the United States, and a resident of Kingston, in the county of Green Lake and 5 State of Wisconsin, have invented certain new and useful Improvements in Loading Apparatus; and I do hereby declare that the following is a full, clear, and exact description thereof.

10 My invention consists in certain peculiarities of construction and combination of parts hereinafter particularly specified with reference to the accompanying drawings and subsequently claimed, its object being to improve 15 the loading apparatus set forth in my Patent No. 795,859, granted August 1, 1905.

Figure 1 of the drawings represents a side elevation of my improved loading apparatus, partly in section; Fig. 2, a similar view of a 20 fragment of the same, having the platform thereof mounted similar to a cart for removal from one place to another; Fig. 3, a front elevation of the loader, partly in section and tipped forward; and Fig. 4, a plan view of the 25 carrier element of said loader in the form of a scraper.

Referring by letter to the drawings, A indicates each of a pair of standards; B, a head-piece in the form of an arch fastened at its 30 ends to the standards; C, a lower beam also fastened at its ends to said standards, and D each of a pair of inclined braces having their upper ends in pivotal connection with the aforesaid standards. The assemblage of 35 parts thus far described constitutes a frame similar to the one set forth in the patent aforesaid. Pivots b engage the lower ends of the frame-braces D and bearings c, depending from the normally inclined platform E of the 40 loader. Suspended under the forward portion of the platform by straps d in connection therewith is a transverse sleeve F, and extending through the sleeve and apertures of the frame-standards is a supporting-rod G, 45 there being apertures at different elevations in said standards to provide for varying the inclination of the platform. Side flanges f of the platform are provided with vertical recesses g near their forward ends for the purpose 50 pose hereinafter set forth, and depending from said platform are hangers h for the axle H of wheels I, that are off the ground when the aforesaid platform is in its inclined position.

55 Depending from the platform is a hanger J, having right-angle side slots i, with which

to engage the ends of a pin j, that extends through one end of a tongue K, engaging said hanger. The platform is provided with a depending bracket L, engaged by the tongue K, 60 and a bolt or pin k engages side apertures of the bracket and an aperture m in said tongue when the latter is drawn forward and the projecting ends of its pin j put into engagement with the slots of the hanger J aforesaid. 65 To provide for balancing load with respect to the tongue, there are side apertures at various elevations of the bracket L, and when the loader is to be removed from one place to another on its wheels the lower beam C, connecting the standards A, is caught in the aforesaid vertical recesses of the side flanges of the platform. A doubletree M is attachable to the tongue, and the working position of said tongue is shown in Fig. 2, its idle position being shown in Fig. 1.

In pivot-bolt connection with the braces D are the branches of a yoke O, in which pulleys P Q are hung, and the yoke branches and said braces are provided with suitably- 80 arranged pivot-apertures to permit variable adjustment of the yoke with respect to that of the platform. To limit back swing of the yoke, the same is connected by chains R to hooks m', with which the standards A are 85 provided, more or less of the chains being taken up on the hooks in proportion to the adjustment of said yoke.

In pivotal connection with the yoke branches is a bail S, and slotted segment ends 90 of the bail are engaged by set-screws n, that turn in said yoke branches and serve to hold said bail in pivotally-adjusted position.

The arch B is provided with a center hanger p for a swivel sheave-block T, and attached to this hanger is one end of a drag-rope U, that extends down under the pulley P and around a pulley V in connection with the triangular swing-bail W of a carrier X, and from this pulley the rope is run forward 100 under the pulley Q and then up through the sheave-block T aforesaid. As shown in Fig. 1, the drag-rope may be run through another sheave-block Y, anchored to the ground forward of the loader.

105 The carrier X is herein shown as having the form of a tilting scraper in pivotal connection with the bail W, and in similar connection with this bail is a longitudinally-slotted lever Z, having a rack portion r thereof engageable with an upper rear bracket s of said carrier to lock said bail forward over

the aforesaid carrier and its load. Engaging the slot in the lever is a pin *t*, that extends laterally from a trip-lever *Z'*, fulcrumed in connection with the carrier, and the bail *S* is 5 adjusted to be in the path of the trip-lever when the carrier has ascent on the platform. The lever mechanism in connection with the carrier is similar to that set forth in my previous patent, and the bail *W* of said carrier 10 is locked in depressed position over the load by the engagement of the rack of lever *Z* with the bracket *s* aforesaid. The loaded carrier is elevated on the inclined platform by draft on the drag-rope *U*, and, the pulley 15 *V*, in connection with the bail *W*, having been brought chock with the pulley *Q* in the yoke *O*, this yoke and parts in connection therewith are swung forward and upward by continued pull on said drag-rope. The carrier 20 being tilted backward by its load, the lever *Z* is caused to strike against the platform and automatically unlatch itself from said carrier. The carrier eventually fulcrums on the platform and automatically tilts in the 25 proper direction to dump its load in or onto a conveyance arranged to receive the same. If by any chance the load in the carrier is so distributed as to prevent said carrier from tilting backward on its way up the platform, 30 and thereby prevent the latch-lever *Z* from coming into contact with said platform, as above specified, the bail *S* in the path of the trip-lever *Z'* will insure the unlatching of said lever *Z* to permit the automatic dumping of 35 the aforesaid carrier at the proper time.

The carrier and its load may be pulled up on the platform and the latter and its frame converted into a conveyance, as above described, to haul said load to a dumping-place, 40 and said platform being tilted back by disconnection of its bracket *L* from the tongue *K* the withdrawal of said carrier to dump its load is facilitated. It also follows that the platform may be loaded and utilized as a cart 45 to transport the load from place to place, the conversion of said platform and frame into such a conveyance being effected in the manner above specified.

I claim—

- 50 1. A loading apparatus convertible to a conveyance and comprising standards, rearwardly-extending inclined braces in pivotal connection with the standards, a platform in like connection with the braces and in detachable connection with said standards, wheels hung underneath the platform, and means in connection with said platform for connection therewith or a draft-tongue, the standards being supported by the aforesaid 55 platform clear of the ground when said loading apparatus is converted into a conveyance.
- 60 2. A loading apparatus convertible to a conveyance and comprising standards, a beam connecting the standards adjacent to 65 their lower ends, rearwardly-extending in-

clined braces in pivotal connection with said standards, a platform in like connection with the braces and in detachable connection with the aforesaid standards, wheels hung underneath the platform, and means in connection 70 with said platform for connection therewith of a draft-tongue, the aforesaid beam being engageable with recesses in side flanges of said platform when said loading apparatus is converted into a conveyance.

3. A loading apparatus convertible to a conveyance and comprising standards, rearwardly-extending inclined braces in pivotal connection with the standards, a platform in like connection with the braces and in detachable connection with said standards, wheels hung beneath the platform, a hanger and bracket suspended from said platform, and a draft-tongue having adjustable support in the hanger and bracket, the standards being supported by the aforesaid platform clear of the ground when said loading apparatus is converted into a conveyance.

4. A loading apparatus convertible to a conveyance and comprising standards, rearwardly-extending inclined braces in pivotal connection with the standards, a platform in like connection with the braces, and in detachable engagement with said standards, a head-piece connecting the standards, a yoke 95 in pivotal connection with said braces, means limiting rearward swing of the yoke, and a carrier having a swing-bail in tackle connection with said head-piece and yoke.

5. A loading apparatus comprising standards, rearwardly-extending inclined braces in connection with the standards, a platform in inclined connection with said standards and braces, a head-piece connecting the aforesaid standards, a yoke in pivotal connection with the aforesaid braces, means limiting rearward swing of the yoke, and a carrier having a swing-bail in tackle connection with said head-piece and yoke.

6. A loading apparatus comprising standards rearwardly-inclined braces in connection with the standards, a platform in adjustable inclined connection with said standards and braces, a head-piece connecting the aforesaid standards, a yoke in adjustable 115 pivotal connection with said braces, means limiting rearward swing of the yoke, and a carrier having a swing-bail in tackle connection with said head-piece and yoke.

7. A loading apparatus comprising standards, rearwardly-inclined braces in connection with the standards, a platform in inclined connection with said standards and braces, a head-piece connecting the aforesaid standards, a yoke in pivotal connection with 125 said braces, means limiting rearward swing of the yoke, a carrier having a swing-bail in tackle connection with said head-piece and yoke, and an automatic release mechanism for locking the bail forward over the carrier 130

for a time in the ascent of said carrier on the platform.

8. A loading apparatus comprising standards, rearwardly-inclined braces in connection with the standards, a platform in inclined connection with said standards and braces, a head-piece connecting the aforesaid standards, a yoke in pivotal connection with said braces, means limiting rearward swing of the yoke, a carrier having a swing-bail in tackle connection with said head-piece and yoke, a lever in connection with the bail and having latch connection with the carrier to lock said bail forward over said carrier, a trip-lever in connection with the aforesaid carrier and latch-lever, and a device in connection with the aforesaid yoke in the path of the trip-lever when said carrier has ascent on said platform.
9. A loading apparatus comprising standards, rearwardly-inclined braces in connection with the standards, a platform in adjustable inclined connection with said stand-

ards and braces, a head-piece connecting the aforesaid standards, a yoke in adjustable pivotal connection with said braces, means limiting rearward swing of the yoke, a carrier having a swing-bail in tackle connection with said head-piece and yoke, a lever in connection with the bail and having latch connection with the carrier to lock said bail forward over said carrier, a trip-lever in connection with the aforesaid carrier and latch-lever, and a device having adjustable connection with the aforesaid yoke to be in the path of the trip-lever when said carrier has ascent on said platform.

In testimony that I claim the foregoing I have hereunto set my hand, at Milwaukee, in the county of Milwaukee and State of Wisconsin, in the presence of two witnesses.

EDMUND RING.
